UNITED STATES PATENT OFFICE.

ABIRAM J. SLONECKER, OF TRENTON, MISSOURI.

WIRE SPLICE.

Application filed April 12, 1924. Serial No. 706,216.

This invention has reference to wire or cable splicers and aims to provide a novel means for splicing wires to insure against movement of one wire with respect to its 5 adjacent wire, eliminating any possibility of the wires becoming accidentally disconnected.

An important feature of the invention is to provide a splicing member on which the wires to be spliced may be readily and easily 10 positioned in the forming of the splice, eliminating the necessity of employing tools in the formation of the splice, the splicer becoming a permanent part of the splice to further strengthen the connection.

15 A still further object of the invention is to provide a splicing member of a construction to accommodate wires of various thicknesses, thereby adapting the device for unlimited use as a splicing member.

20 A still further object of the invention is to provide a splicing means whereby insulated wire may be spliced, eliminating any possibility of damaging the insulation.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, may be made within the scope of what is claimed, without departing from the spirit of the invention.

Referring to the drawing:

35 Figure 1 is a plan view disclosing a splicing member constructed in accordance with the invention, and the wires spliced thereon;

Fig. 2 is an end elevational view of the splicing member;

40 Fig. 3 is a plan view disclosing a modified form of the splice;

Fig. 4 is a sectional view taken on line 4—4 of Figure 3;

Fig. 5 is a further modified form of the 45 splice; and

Fig. 6 is a still further modified form of the splicing member disclosing hooks at the ends thereof.

Referring to the drawing in detail, the 50 splicer includes an elongated body portion indicated generally by the reference character 5 which is formed with offset portions 6 arranged in spaced relation with each other throughout the length of the body portions,

55 and disposed on opposite sides of a line drawn centrally through the body portion.

At the ends of the body portion are provided hook members 7 constructed by bending the ends of the body portion upwardly, which hook members are adapted to engage the 60 wires being spliced to hold them against lateral movement with respect to the splicing member or body portion 5.

As clearly shown by Fig. 4, the offset portions 6 are arranged in staggered relation 65 with each other at opposite sides of a vertical line drawn through the structure, whereupon the wires being spliced may be readily inserted between the offset portions to secure the wire to the splicing member. 70 It is to be understood that this form of splicing member is especially designed for use in splicing insulated electric lead wires to a main line wire where it is desired to take off electric current from a main wire, thereby 75 providing means for supporting a wire and at the same time relieve the wire of undue strain at its point of connection with the main wire. This form of splicer is also especially adapted for use in splicing relatively 80 large wires that are not so pliable as the smaller gage wire.

In the form of the invention as illustrated by Fig. 5, the length of wire forming the body portion is bent to provide a plurality 85 of offset portions 8 which are connected by angular portions 9 providing relatively large spaces between the offset portions to admit the wires being spliced. Thus it will be seen that due to this construction the wires when 90 wrapped spirally in forming a splice will have a greater length of contact with the splicing member at 9 as well as with each other, to insure a secure splice.

Hook members 10 are also formed at the 95 ends of the body portion in this form of the invention and are designed to engage the wires being spliced to prevent lateral movement thereof when a splice has been made. As shown, to further insure against movement of one wire with respect to the wire spliced thereto, the ends of the wires being spliced are coiled or wrapped around the adjacent wires at 11 providing a structure 100 which is absolutely secure.

As illustrated by Fig. 6, the splicing member is in the form of a length of wire bent to provide lateral loops 12 in which the wires being spliced are positioned in 105 such a manner that they will overlap each other at points between the loops. The ends of the splicing member are formed into 110

oppositely disposed hooks 13 to be engaged by the wires.

In the forming of a splice in accordance with the invention, a splicing member as shown is held in the hands of the person making the splice and the ends of the wires to be spliced are positioned on the splicing member in a manner as shown by the several figures of the drawing, the splicing 10 being accomplished by passing the wires to the splicer in opposite directions over the splicing member, the wires being wound around the portions of the splicing member connecting the offset portions thereof in 15 such a way that they cross each other at these points. In the final completion of the splice, the wires are secured to their adjacent wires at the ends of the splicing member.

20 While I have shown and described a splicing member and method of forming a splice, it is to be understood that a splicer of this character may be efficiently employed for splicing electric wires, fence

wires, baling wires, or the like, eliminating 25 the necessity of soldering or twisting the wires together, as is common practice and which requires the use of tools to insure a strong splice.

The splicing member may also be efficiently used as a securing member for the end of a guy wire whereupon the end of the guy wire may be secured against accidental displacement.

I claim:—

A splicer including a length of wire having a plurality of offset portions formed throughout its length, said offset portions being extended laterally in the same direction, said offset portions being arranged in 40 staggered relation with each other to provide grooves between adjacent offset portions, and said grooves and offset portions adapted to receive wires to be spliced.

In testimony that I claim the foregoing 45 as my own, I have hereto affixed my signature.

ABIRAM J. SLONECKER.
